UNITED STATES PATENT OFFICE.

JOSEPH C. GILARDONE, OF FLEETWOOD, PENNSYLVANIA.

VEHICLE SPRING.

Application filed March 6, 1925. Serial No. 13,449.

To all whom it may concern:

Be it known that I, JOSEPH C. GILARDONE, a citizen of the United States, residing at Fleetwood, in the county of Berks and State 5 of Pennsylvania, have invented certain new and useful Improvements in Vehicle Springs, of which the following is a specification.

This invention relates to improvements in 10 springs and it is intended more particularly for use in connection with vehicle springs made up of a plurality of leaves.

The object in the present invention is to 15 provide a spring of this character in which the tendency to "squeak" is reduced to a minimum.

My invention consists of providing each 20 leaf of the spring with a relatively soft metal strip extending across the leaf at each end, and adapted to contact with the upper surface of the leaf next to it.

The invention is more fully described in 25 the following specification and clearly illustrated in the accompanying drawing, in which:—

Figure 1 is a plan view of my spring.

Figure 2 is a side elevational view thereof.

Figure 3 is a sectional view taken through 30 3—3 Fig. 1.

Figure 4 is a detail view, enlarged, of 35 one of the ends of a leaf of the spring.

The numeral 1 designates the spring, which is made up of a plurality of leaves of metal 2, as usual. In my present structure 40 however, I upset the ends of each leaf, as indicated at 4, bringing it to an appreciable

distance above the surface of the leaf immediately beneath it. Immediately beneath these upset ends, I place a strip of relatively soft metal 5, which is attached to the spring 45 leaf by means of screws 6 or other suitable means, so that these strips may be removed and replaced when worn.

These strips extend the full width of the leaf, and when the spring is depressed, as 50 when the load is applied, they will move along the surface of the leaf beneath them but this movement will be a silent one, due to the soft metal, and, inasmuch as this frictional engagement of the ends of the spring 55 leaves with the surfaces of the next leaf beneath it, causes the greater part of the so-called "squeak" in springs, it is evident that with my present structure, this noise will be almost if not entirely eliminated.

This structure will to a very great extent 60 overcome the need of lubricating the springs.

Having thus described my invention, I 65 claim and desire to secure by Letters Patent:—

In a vehicle spring, a plurality of superimposed plates of spring metal, each plate having both of its ends turned downwardly away from the surface of the plate next above it, a strip of relatively soft metal, 70 equal in length to the width of the plates, secured to the upper surface of each turned end by means of a pair of screws, and adapted to bear against the surface of the plate next above it.

In testimony whereof I affix my signature.

JOSEPH C. GILARDONE.
